UNITED STATES PATENT OFFICE.

FREDERICK GRAB, OF NEW YORK, N. Y.

ENVELOP.

1,019,783.

Specification of Letters Patent. Patented Mar. 12, 1912.

Application filed December 28, 1910. Serial No. 599,746.

To all whom it may concern:

Be it known that I, FREDERICK GRAB, a citizen of the United States, residing at New York, county of New York, and State 5 of New York, have invented certain new and useful Improvements in Envelops, of which the following is a specification.

My invention relates to envelops and the object of my invention is to provide an envelop 10 which may be readily and quickly opened, but which cannot be opened without detection.

Other objects will appear hereinafter.

My invention consists in the envelop hereinafter described and particularly pointed out in the claims and in the blank from which the envelop is formed.

My invention will be more readily understood by reference to the accompanying 20 drawing forming a part of this specification and in which—

Figure 1 is a view of the blank from which the envelop is formed, Fig. 2 is a rear elevation of the envelop completely formed 25 and illustrating the flap in open position, Fig. 3 is a front elevation of the envelop with the flap opened, and Fig. 4 is a similar view illustrating the same closed and sealed and ready for mailing.

30 Referring now to the drawing 1 indicates the blank from which the envelop is formed and 2 the completed envelop. The body of the envelop comprises a front 3 which is adapted to bear the address, and a back 35 consisting of a wide flap 4 and a narrow flap 5 which are folded inwardly from the upper and lower edges 6 and 7 of the portion 3. The edge of the flap 5 overlaps the edge of the flap 4 and is gummed as at 8 to 40 secure the overlapping edges together. The edges of the flaps 4 and 5 lie parallel with the edges 6 and 7 of the portion 3.

Projecting from one end of the portion 3 is a flap 9. This is quite short but 45 extends the full width of the end of the front 3 and is provided with gum 10 by means of which it is secured to the ends or lateral edges of the flaps 4 and 5 which it overlaps as shown clearly in Fig. 2.

50 The opposite end of the flap 5 from that to which the flap 9 is attached when folded is enlarged forming a projecting tongue 11, the combined length of the flap 5 and tongue 11 being equal to the distance between the 55 upper and lower edges 6 and 7 of the front 3. The tongue 11 extends both above and

below a line 12 in alinement with the end of the front 3 along which said tongue is folded forming a portion 13 which overlaps the adjacent end of the flap 4 and a closing flap 14. The edge of the portion 13 is gummed as at 15 to secure it to the flap 4, thus completing the envelop. The flap 14 is provided with an integral longitudinally extending tab 16 the purpose of 60 which will be described. The flap 14 is gummed each side of the tab 16 as at 17 and 17' for sealing the envelop, but the gum is omitted opposite the tab 16 as indicated at 18 in Figs. 1 and 3. After the envelop 70 is closed and sealed the postage stamp 18 is attached to the flap 14 and front 3 as indicated in Fig. 4 so that the flap cannot be opened without disturbing the stamp. If preferred the gum 17' may be omitted as 75 this end of the flap is secured by the stamp. To open the envelop the tab 16 is grasped and given a sharp pull outwardly which will open the envelop.

The envelop herein illustrated and described is of simple construction, may be readily opened by the party to whom it is sent but is proof against opening without detection. On the outer face of the tab 80 16 is printed the word "Pull" together with an arrow to indicate the direction in which to pull the tab as shown at 19 in Fig. 4. If desired a business card 20 may be printed in the usual place on the front of the envelop. It will be noted that with the construction set forth the printing on the face 85 of the envelop and on the tab is upon one side only of the blank and that all of the gum is arranged upon one face of the blank which facilitates printing and gumming the 90 same.

Having described my invention what I claim as new and desire to secure by Letters Patent is:

1. In an envelop, a body portion comprising a front and a back, the back consisting of a long and a short flap folded inwardly from opposite edges of the front and having overlapping gummed edges, a flap extending from one end of said front and overlapping and gummed to the adjacent ends of the back flap and a tongue extending from the opposite end of the short back flaps and folded to form a portion which is gummed to the end of the long back flap and a closing flap, and a tab projecting from the closing flap, substantially as described. 100 105 110

2. A blank for forming an envelop comprising a rectangular front forming portion, a long and a short back flap portion projecting from the opposite long sides of the front forming portion, an end flap extending from one of the short ends of the front forming portion and a tongue extending from one end of the short back flap portion in alinement with the adjacent end of the front portion and extending both above and below said end and with said short back

flap extending the full width of the adjacent short end and a tab projecting from the outer edge of said tongue, substantially as described.

15

In testimony whereof I have signed my name to this specification in the presence of two subscribing witnesses.

FREDERICK GRAB.
